(57) CLAIM

The ornamental design for a disposable backless bra, as shown and described.

DESCRIPTION

FIG. 1 is a perspective view of the disposable backless bra showing my new design;

FIG. 2 is a front elevational view of the disposable backless bra, shown in FIG. 1; and,

FIG. 3 is a rear elevational view of the disposable backless bra, shown in FIG. 1.

The broken lines on the front and rear surface of the disposable backless bra are understood to represent stitching.
